UNITED STATES PATENT OFFICE.

WILLIAM BUNTING, JR., OF BROOKLINE, MASSACHUSETTS.

DESIGN FOR A TRAP-BODY.

SPECIFICATION forming part of Design No. 32,657, dated May 15, 1900.

Application filed April 18, 1900. Serial No. 13,392. Term of patent 14 years.

To all whom it may concern:

Be it known that I, WILLIAM BUNTING, Jr., a citizen of the United States, residing at Brookline, county of Norfolk, and State of Massachusetts, have invented and produced a new and original Design for Trap-Bodies, of which the following is a specification, reference being made to the accompanying drawings, forming a part thereof.

10 Figure 1 is a front elevation of the trap-body, showing my new design; and Fig. 2 is a side elevation thereof.

As shown in the drawings, the leading or material feature of my design consists of a 15 waste-pipe-trap body having the down leg thereof formed by a pipe A, which is bent in a circular or annular form. An inlet-pipe B is connected to the annular pipe A at the top of the ring formed thereby, and the outlet-pipe C is connected to the rear side of the 20 annularly-bent pipe and at the lower portion thereof. The outlet-pipe C extends upwardly and rearwardly from its point of connection with pipe A and is formed with two bends or

curves. Both inlet and outlet pipes have 25 their center lines in a plane through the vertical diametrical line of the annularly-bent pipe A and at right angles to the central plane of the latter. The surface of all the pipes is plain and without ornamentation of any sort, 30 the design simply relating to the configuration of the main body of the trap and not relating in any manner to the form of connections to the inlet and outlet pipes or to the clean-out opening.

Having described my invention, what I claim as new, and desire to secure by Letters Patent of the United States, is as follows:

The design for a trap-body, as herein shown and described.

In testimony whereof I sign my name, on this 13th day of March, in the year 1900, in the presence of two witnesses.

WILLIAM BUNTING, JR.
